UNITED STATES PATENT OFFICE.

ROBERT G. C. BOA, OF CHICAGO, ILLINOIS, ASSIGNOR TO REMINGTON ACCOUNTING MACHINE CORPORATION, OF NEW YORK, N. Y., A CORPORATION OF NEW YORK.

CALCULATING MACHINE.

1,418,062.

Specification of Letters Patent. Patented May 30, 1922.

Application filed April 21, 1921. Serial No. 463,154.

To all whom it may concern:

Be it known that I, ROBERT G. C. BOA, citizen of the United States, and resident of Chicago, in the county of Cook and State of Illinois, have invented certain new and useful Improvements in Calculating Machines, of which the following is a specification.

My invention relates to calculating machines and is embodied in the present instance in a Remington-Wahl combined type-writing and calculating machine of the character known on the market as a "cross footer," and which machine is disclosed in the patent to John C. Wahl #1,270,471, dated June 25, 1918; although it should be understood that the invention is not restricted to embodiment in such machines.

In the construction disclosed in the said patent certain of the "vertical totalizers" which are carried by and adjustable along the carriage are provided with two different sized cams detachably fixed thereto. These cams are adapted, during the travel of the carriage, to coact with a follower which forms part of the actuator-control or gear shifting mechanism of the cross totalizer. When a cam coacts with the follower the movement of the latter actuates the control mechanism to bring about, at the operation of a numeral key, either subtraction in the cross totalizer, or to disconnect and render the latter inoperative, depending on the character or size of the cam in operation.

In accordance with the present invention I provide on each vertical totalizer, or on each of a number of "dummies" which may be substituted for such totalizers if desired, a cam which is adjustably mounted thereon so that it may be set to coact with a follower such as that referred to above, in the same manner as the two different sized cams disclosed in said patent, and also to obtain a setting of each of said cams for addition. In the patent to John C. Wahl, #1,349,024, dated August 10, 1920, there is disclosed two adjustable cams on each vertical totalizer to coact with the control mechanisms of two cross totalizers.

One of the main objects of my present invention is to provide an improved adjustable cam mechanism of the general character specified. A further object of the invention, generally stated, may be said to be to provide simple, strong and efficient means for

effecting an adjustment of a cam on a carrier, or totalizer, carried by the carriage, whereby said cam may be readily and accurately set and effectively and firmly held in any one of several positions to coact with the follower of a totalizer-actuator control mechanism.

To the above and other ends which will hereinafter appear my invention consists in the features of construction, arrangements of parts, and combinations of devices set forth in the following description and more particularly pointed out in the appended claims.

In the accompanying drawings wherein like reference characters indicate corresponding parts in the various views,

Fig. 1 is a fragmentary front elevation showing a portion of a Remington-Wahl cross footing machine equipped with two different sized vertical totalizers, the right-hand totalizer 5 being provided with one form of cam adjusting devices embodying my invention, and the left-hand totalizer 5^a being provided with a slightly different form of cam adjusting devices embodying the invention.

Fig. 2 is an enlarged detail fragmentary front view, with parts broken away, of a detached vertical totalizer, "dummy," or carrier 5 such as is shown at the right in Fig. 1.

Fig. 3 is a fragmentary vertical fore-and-aft sectional view of the same taken on the line 3—3 of Fig. 2 and looking in the direction of the arrow at said line.

Fig. 4 is a horizontal sectional view of the same taken on the line 4—4 of Fig. 2 and looking in the direction of the arrow at said line.

Fig. 5 is a detail fragmentary front view of a portion of the locking plate of the carrier 5.

Fig. 6 is a view in section through the carrier on the line 6—6 of Fig. 2 and looking in the direction of the arrow at said line.

Fig. 7 is an enlarged detail side view with parts in section of the totalizer, "dummy" or carrier 5^a, the same being shown detached and the section being taken on the line 7—7 of Fig. 9 and looking in the direction of the arrow at said line.

Fig. 8 is a horizontal sectional view of the same taken on the line 8—8 of Fig. 9

and looking in the direction of the arrow at said line.

Fig. 9 is an enlarged detail fragmentary front elevation, with parts sectioned away, 5 of the carrier 5^a and the cam-adjusting means.

In the drawings I have illustrated only so much of a Remington-Wahl cross footing machine as may be necessary to arrive at an 10 understanding of my invention in its embodiment therein; various of the details of said machine not shown in the accompanying drawings being well known in the art and fully illustrated in the hereinbefore 15 mentioned Patent #1,270,471.

It will be understood that, in the present instance, the follower 1 carried by a crank arm 2 which is mounted on a rock shaft pivoted in the fixed actuator frame 3, may 20 be connected in the usual manner with the actuator-control or gear shifting mechanism of the cross footer (not shown), as is fully illustrated in the said Patent #1,270,471. As is well understood, the follower 1 in its 25 lowermost position sets the control mechanism of the cross footer for "subtraction," whereas, the uppermost position of said follower, to which it is moved by a spring, sets said control mechanism for "addition." An 30 intermediate position of said follower, under control of a cam, results in said control mechanism being set to disconnect the actuator of the cross footer.

The member 4 which is, or may be, of 35 the usual construction, and is sometimes referred to as the "vertical" or main truck or calculator carriage is connected to travel right and left with the typewriter carriage. One or more so-called "vertical totalizers" 40 5 or 5^a are detachably mounted on the truck 4, and each is adjustable to different set positions along the truck, where it may be held by a spring-pressed, hand released latch 6 or 6^a adapted to engage teeth 7 on the truck.

45 The adjustable cam of my invention, which coacts with the follower 1 to automatically position the actuator-control or gear shifting mechanism, in some instances is mounted on each of the vertical totalizers 50 5 or 5^a. In other instances it is mounted on a so-called "dummy," which may comprise a frame such as the frame of a totalizer 5 or 5^a but which contains no totalizer mechanism therein and merely constitutes an adjustable carrier for the adjustable cam, and 55 for other parts, such for example as the "heel" 8 (see Fig. 7) for the pick-up beam (not shown). Each of these "dummies" is intended to be used in the place of a totalizer 60 5 or 5^a where the character of the work is such that no computation is to be entered in a vertical totalizer within the field occupied by the "dummy." With this explanation in mind it will be understood that 65 when I refer herein to a "carrier" for the

cam, such term is intended to apply to the support on which the cam is adjustably mounted whether such support be a totalizer 5 or 5^a, a "dummy," or other form of support for the cam.

70 I have shown my invention in two forms, one illustrated in Figs. 2-6, inclusive, being adapted for a wide totalizer and the other, shown in Figs. 7, 8 and 9, being adapted for a narrow totalizer. The two forms are constructed on the same principle but differ as to certain details.

I will first describe the construction disclosed in Figs. 2 to 6 inclusive. The frame 75 of a totalizer 5, or a corresponding "dummy," has its parallel side plates 9 apertured at 10 to receive and have seated therein lugs or reduced end portions 11 of a vertically disposed supporting plate 12, thus fixedly securing said plate to the frame. 80 Projecting forwardly from said supporting plate, about midway in the length thereof, is a supporting stud 13. This stud is riveted at its rear end, as at 14, to the supporting plate, and is interiorly tapped at its forward 85 end to receive a headed screw 15. The stem of this screw passes through a hole in a fixed locking and guiding plate 16, while the head of the screw bears against the forward face of the plate, thus fixedly connecting the 90 lower end of the locking plate to the carrier and maintaining the plate in front of and spaced away from the frame of the carrier. The upper end of the locking plate 95 is secured to the carrier, as best shown in Fig. 6, by riveting forwardly projecting hollow supporting studs 17 to the front cover plate of the frame, as indicated at 18. The forward end portion of each stud 17 is reduced at 19 forming a shoulder 20. The reduced end of each stud is received in a hole in the locking plate, the plate being held against the shoulder 20 on the stud by the head of an associate screw 21, the stem of which is threaded into the interiorly tapped 100 opening in its stud. The plate 16 is thus 105 fixedly held on the carrier by the screws 15 and 21.

110 Arranged parallel with and bearing against the front face of the supporting plate 12 is the adjustable cam plate 22, its lower edge constituting an actuating cam 23. The plate 22 is slotted at 24 to enable the stud 13 to pass freely therethrough and not interfere with a rectilinear up and down adjustment of the cam plate. The side edges 115 25 of the plate 22 coact with the inner faces of the overlapping parallel side plates 9 of the frame, thus preventing a longitudinal displacement of the plate 22 and guiding the latter in its up and down adjustments. Intermediate the locking plate 16 and the body portion of the frame, is a plate 26, which in the present instance comprises a cross bar 27 from which an upwardly projecting arm 120 125

130

28 extends. The cross bar is fastened near its ends to the plate 22 by two intermediate shouldered rivets 29, each riveted at one end 30 to the cross bar 27 and at the other end 5 31 to the plate 22. In this manner, the parallel plates 26 and 22 are fixedly connected to move together as one piece, the plate 22 being off-set rearwardly with reference to the plate 26 so that the cam 23 may coact 10 with the follower 1.

The plates or members 27-28 and 22 are in effect one piece, and from certain aspects of my invention may be so regarded. In order to adapt the construction to the Remington-Wahl machine, as at present constituted, the member 22 is located beneath the body portion of the totalizer or "dummy" where it is required to coact with the follower 1. On the other hand, the member 20 27-28, and the means which coact therewith to effect an adjustment of the cam, are off-set forwardly so as to bring these parts in front of the totalizer where sufficient room is provided therefor and where they 25 are readily accessible to the operator for purposes of adjustment. I have heretofore pointed out that the side edges 25 of the cam plate 22 coact with the side plates 9 of the totalizer frame to guide said cam plate and 30 prevent a right and left-hand movement thereof (and the parts fixed thereto) relatively to the totalizer frame. These parts 22 and 27-28 are guided front and rear and prevented from fore-and-aft displacement 35 on the frame of the totalizer by the fixed plates 12 and 16. The former coacts with the plate 22 to prevent a rearward displacement of the parts whereas the plate 16 coacting with an intermediate member 40 35, to be hereinafter described, prevents a forward displacement of the connected parts 22 and 27-28. The arm 28 is arranged centrally of the cross bar 27, and carries near its upper end a forwardly projecting 45 headed pin 32, riveted thereto at 33 and passing through a vertically disposed slot 34 in the fixed plate 16; the slot 34 extending in the same direction and being located in the same fore and aft plane as the slot 24 50 in the plate 22. It will be seen that the pin 32 is arranged at about equal distances from the ends of the cam plate 22, or the bearing portions 25 thereof, so that an up and down movement transmitted to the pin is 55 effective to move the plates 26 and 22 together without the latter binding at its guiding surfaces.

An upright arm, member or link 35 is pivoted at its upper end on the pin 32 so 60 as to be connected to the plate 26 (and to the cam 23 movable with said plate) to have a bodily up and down movement therewith, and also to have a pivotal movement relatively thereto. The lower end of the link 65 carries a forwardly projecting pin 36, riv-

eted thereto at 37, and formed with a head 38 at its forward end. This pin extends through a guide slot 39 in the fixed locking plate 16. In the present instance this slot is of angular formation and its walls constitute in effect a cam fixed on the carrier and one which is substantially V-shaped and enables the pin to be displaced to three different set positions in the slot of the cam. Thus, when the pin is moved to the lower end of the slot, as shown in Fig. 2, the cam 23 will be moved to its lowermost position to coact with the follower 1 and set the gear shifting mechanism of the cross foot totalizer for subtraction. When the pin is moved to the upper end of the angular slot, as shown in Fig. 1, the cam 23 will be adjusted for addition, and when the pin is moved to the intermediate position the adjustable cam will be set for "disconnect". The cam is set to its "disconnect" position by moving the finger piece 40 leftward as far as it will go. I have provided on the front face of the locking plate 16 three symbols "A", "D", "S", each arranged adjacent to that part of the cam slot 39 to which the symbol corresponds, so as to aid the operator in setting the adjustable cam 23 by bringing the pin 36 to its proper position relatively to the slot 39 for addition, disconnect, or subtraction, as indicated respectively by the symbols "A", "D", "S".

It will be seen that each of these three positions of adjustment of the cam plate 22 is accurately attained and positively determined by bringing the pin 36 at one movement to an end wall of a slot, i. e., either the upper or lower right-hand end of the slot or the left-hand end thereof, where the symbol "D" appears. If it is borne in mind that in actual practice the extent of adjustment of the cam plate 22 from its highest point indicated by the symbol "A" to its lowest point indicated by the symbol "S" is only about one-eighth of an inch, then it will be understood how important it is to provide means for accurately and positively defining these three positions of adjustment of the cam, and for positively and accurately holding the cam against accidental displacement from any of these positions to which it may be adjusted. The difficulty of providing efficient means for a construction of this kind by reason of this fine adjustment and the small space which may be allotted to some of the parts will also be better appreciated, as will the advantages in this connection of the V-shaped guide slot 39.

In order to aid the operator in setting the hand-controlled pin 36, and in order to lock it and the parts controlled thereby in different set positions to which they may be adjusted, I loosely mount on the pin 36 a finger piece 40 by which the pin and the parts controlled thereby may be moved.

The outer end of this finger piece has an enlarged opening 41 in which the head 38 of the pin is received. The bottom wall 42 of this opening forms a bearing against 5 which one end of a coiled expansion spring 43 is seated; said spring surrounding the pin, and bearing at its opposite end against the head 38. The spring 43 tends to move the finger piece rearwardly to the position 10 shown in Fig. 3, but enables it to be moved forward on the pin to release the lock which holds the link 35, and the parts on the carrier controlled thereby, in any of the three set positions to which they may be adjusted. 15 Thus, the rear end portion of the finger piece is reduced to form a rounded locking member or spring-pressed locking plunger 44 which is adapted to seat itself in any of three locking notches, recesses or depressions 45 in the front face of the locking plate 16 when brought into register therewith. When the locking member is seated in one of the depressions 45 an interlocking positive connection with the plate 16 is 20 established which prevents a displacement of the pin 36 in its slot 39 until the locking member 44 is withdrawn. This may be readily effected by sliding the finger piece 40 forward on the pin 36 against the force 25 of the spring 43. The pin may then be adjusted to a new position along the slot 39 with the aid of the finger piece, and again locked in such new position; causing the 30 parts on the carrier controlled by the link 35 to be locked against movement on the carrier. As hereinbefore pointed out, the cam adjusting means illustrated in Figs. 7, 8 and 9 are intended more particularly for a comparatively narrow carrier, the one shown being 35 a three-wheel totalizer. Many of the details of this construction are similar to those previously described, and to avoid repetition of description, various of the parts in the construction which correspond 40 to those previously described will be designated by corresponding reference numerals with the exponent α added thereto.

In the modified construction the locking plate 16 α is connected to the carrier 5 α in a 50 different manner from that previously described. Thus the parallel side plates 9 α of the carrier 5 α are extended further forward than the corresponding plates of the other construction, and receive between them 55 the locking plate 16 α . Each side plate 9 α is apertured at two points 46 to receive outwardly extending lugs 47 on a side edge of the locking plate 16 α , and thus fixedly secure the plate 16 α to the frame. The plate 60 26 α , to which the cam carrying plate 22 α is fastened by shouldered rivets 29 α , has its lower parallel side edges 48 arranged to coat with the inner faces of the side plates 9 α of the carrier, thereby guiding the plate 65 26 α and its up and down adjustment, as well

as directly guiding the cam plate by having the parallel side edges of the latter coat with side plates 9 α , as in the previously described construction. The upper portion of the side edges of the plate 26 α are cut away, 70 as indicated at 49, thus producing an upwardly extending arm 28 α . A pin 32 α , to which the link 35 α is connected, is secured to the upper end portion of the arm 28 α . The stud 13 and the screw 15 are omitted. 75 Otherwise the parts are essentially the same as those previously described, and are operated in a like manner.

From the foregoing description it will be understood that the pivotal movement 80 of the link 35, or 35 α , relatively to the adjustable cam 23, or 23 α respectively, is governed by the walls of the guide slot 39, or 39 α respectively, which constitute a fixed part of the carrier, and that such relative 85 movement of the link, governed in the manner stated, effects an up and down adjustment of the adjustable cam and determines the extent of such adjustment. While I prefer to make the slot 39, or 39 α , in the nature of a guide slot, by which a camming action may be effected, from certain aspects of my invention this is unnecessary. Nor is it essential from certain aspects of the invention that the fixed guide on the carrier, with 90 which the link coacts to regulate the adjustment of the adjustable cam, shall be formed by slotting the locking plate. Generally stated, the invention involves governing means which coacts with the link to 95 govern its movement relatively to the adjustable cam, and to thereby determine the extent of bodily movement of the link and the adjustment of the adjustable cam which moves bodily therewith. The invention also 100 will be understood, generally stated, to include a link or member pivotally connected at one end with the adjustable cam and adapted to move bodily therewith, with means for connecting the other end of the 105 link at any one of a number of different points on a fixed plate carried by the carrier, and thus adjust and hold the cam in its adjusted position.

It will be seen that in the present construction the manner of mounting the adjustable cam and the parts by which it is adjusted and locked in adjusted position, is such that they cannot drop, or be accidentally detached, from the carrier, which detachment 110 might result in the parts in question being misplaced or lost.

Various changes may be made without departing from my invention.

What I claim as new and desire to secure 115 by Letters Patent, is,

1. In a calculating machine, the combination of a carriage, a follower forming part of a totalizer-actuator control mechanism, a carrier adjustable to different positions along 120

130

- said carriage, a cam adjustable on said carrier and co-operative with said follower, a guide fixed on the carrier, and an operating member connected to said cam and engaging 5 and movable bodily along and guided by said guide and which determines the point of adjustment of the adjustable cam by the adjustment of said operating member along the fixed guide.
- 10 2. In a calculating machine, the combination of a carriage, a follower forming part of a totalizer-actuator control mechanism, a carrier adjustable to different positions along said carriage, a cam adjustable on said carrier and co-operative with said follower, a guide cam fixed on the carrier, and a connecting member operatively connected at one end with said adjustable cam and co-operative at its other end with said fixed guide 15 cam to effect a camming action on said connecting member and thereby adjust the adjustable cam.
3. In a calculating machine, the combination of a carriage, a follower forming part 20 of a totalizer-actuator control mechanism, a carrier adjustable to different positions along said carriage, an actuating cam mounted to receive a rectilinear adjustment to different positions on said carrier and to coact with 25 said follower, a hand-controlled adjusting link pivotally connected with said adjustable cam to move bodily therewith and to receive a pivotal movement relatively thereto, and a guide fixed to said carrier and with which 30 said link coacts, the position of the link relatively to said fixed guide determining the 35 position of rectilinear adjustment of said actuating cam.
4. In a calculating machine, the combination 40 of a carriage, a follower forming part of a totalizer-actuator control mechanism, a carrier adjustable to different positions along said carriage, a cam adjustable on said carrier and co-operative with said follower, and 45 means for controlling the adjustment of said cam comprising a link pivoted to a part fixed to move bodily with said cam so that said cam and link move together bodily and the link may turn relatively to said cam, a fixed 50 part of the carrier having a slot therein, and a connection from said link to said slot, whereby a displacement of said connection in the slot will change the position of the link and thus determine the adjustment of 55 said adjustable cam.
5. In a calculating machine, the combination 60 of a carriage, a follower forming part of a totalizer-actuator control mechanism, a carrier adjustable to different positions along said carriage, two parallel plates one fixed to the carrier and the other adjustable thereon and carrying a cam, one of said plates having a slot therein, and a link intermediate 65 said plates and pivoted to one of them and having a camming action in the slot of the other plate so that the position of the link relatively to the slot determines the position of adjustment of said adjustable cam.
6. In a calculating machine, the combination 70 of a carriage, a follower forming part of a totalizer-actuator control mechanism, a carrier adjustable to different positions along said carriage, a cam adjustable on said carrier and co-operative with said follower, and 75 means for controlling the adjustment of said cam comprising a link pivoted to a part fixed to move bodily with and relatively to said cam, a relatively fixed part with a slot therein having walls that act as a cam, a connection from said link to said slot whereby a 80 displacement of said connection in the slot will change the position of the link and thus determine the adjustment of said adjustable cam, and means for locking said link at any 85 of several different positions to which it may be adjusted in said slot.
7. In a calculating machine, the combination 90 of a carriage, a follower forming part of a totalizer-actuator control mechanism, a carrier adjustable to different positions along said carriage, two parallel plates one fixed to the carrier and the other adjustable thereon and carrying a cam, a link intermediate 95 said plates and pivoted to one of them and connected to the other by a guide slot therein having inclined walls that act as a cam so that the position of the link relatively to the slot determines the position of adjustment of said adjustable cam, a hand-controlled member connected to said link for shifting it to different positions in the guide slot, locking means for locking said hand-controlled member in any of several different 100 positions to which it may be shifted with said link, and means for affording a movement of said hand-controlled member independently of said link to control the engagement and release of said locking means.
8. In a calculating machine, the combination 105 of a carriage, a follower forming part of the totalizer-actuator control mechanism, a carrier adjustable to different positions along said carriage, a cam adjustable on the carrier and co-operative with said follower, and 110 means for controlling the adjustment of said cam comprising a member connected with said cam to receive a bodily movement therewith and also to receive a movement relatively thereto during the adjustment of the cam on its carrier, and means coacting with said member to govern its said relative movement and thus determine the bodily movement thereof and the adjustment of the cam connected therewith.
9. In a calculating machine, the combination 115 of a carriage, a follower forming part of the totalizer-actuator control mechanism, a carrier adjustable to different positions along said carriage, a cam adjustable on the 120
- 125
- 130

carrier and co-operative with said follower, and means for controlling the adjustment of said cam comprising a member connected with said cam to receive a bodily movement therewith and also to receive a movement relatively thereto, a finger piece connected with said member for moving it, and a relatively fixed guide which governs the movement of said member when moved by its finger piece, the said member and fixed guide then controlling the adjustment of said cam.

10. In a calculating machine, the combination of a carriage, a follower forming part of a totalizer-actuator control mechanism, a carrier adjustable to different positions along said carriage, an actuating cam adjustable on the carrier and co-operative with said follower, and means for controlling the adjustment of said cam comprising a governing member having a substantially V-shaped opening or slot therein, and a hand-controlled member connected with said actuating cam and having a part entering the V-shaped slot and governing by its movement 25 along said slot the adjustment of the actuating cam.

11. In a calculating machine, the combination of a carriage, a follower forming part of a totalizer-actuator control mechanism, a carrier adjustable to different positions along said carriage, an actuating cam adjustable on the carrier and co-operative with said follower, and means for controlling the adjustment of said cam comprising 30 a governing member fixed to said carrier and having an angular opening or slot therein, a member connected with said actuating cam and having a part entering said slot and locating the actuating cam in different 35 adjusted positions according to the disposition of said part at different points along said angular slot, a finger piece connected to said member for adjusting it, and locking means at different points along the angular 40 slot for co-operation with said finger piece to lock said member and the adjustable cam controlled thereby in different positions to which they may be adjusted.

12. In a calculating machine, the combination of a carriage, a follower forming part of a totalizer-actuator control mechanism, a carrier adjustable to different positions along said carriage, a cam adjustable on said carrier and co-operative with said follower, 55 a plate fixed on said carrier and having a slot therein, a member connected with said cam and having a pin received in and adjustable along said slot, and means for retaining the pin at any one of a number of 60 different points along the slot, thereby determining the point of adjustment of said cam and holding it in its adjusted position.

13. In a calculating machine, the combination of a carriage, a follower forming 65 part of a totalizer-actuator control mecha-

nism, a carrier adjustable to different positions along said carriage, a cam adjustable on said carrier and co-operative with said follower, a plate fixed to said carrier and having a slot therein, a member connected with said cam and having a pin received in and adjustable along said slot, a finger piece carried by said pin and adapted to slide thereon, said plate having a series of locking recesses therein at different points along 70 the slot and in each of which a part of the finger piece is adapted to seat itself to lock said member and the cam controlled thereby in adjusted position, and a spring which exerts its pressure on the finger piece and tends 75 to move it into locking engagement in any one of said locking recesses.

14. In a calculating machine, the combination of a carriage, a follower forming part of a totalizer-actuator control mechanism, a carrier adjustable to different positions along said carriage, a cam adjustable on said carrier and co-operative with said follower, a pin located about equal distances from the ends of said cam and operatively 85 connected to move therewith, a plate fixed to said carrier and having a slot along which said pin is adapted to move, a link pivoted at one end on said pin and adapted to move bodily therewith as well as to turn thereon, 90 and means for connecting the other end of said link to said fixed plate at any one of a number of different points and thus adjust the cam and hold it in its adjusted position.

15. In a calculating machine, the combination of a carriage, a follower forming part of a totalizer-actuator control mechanism, a carrier adjustable to different positions along said carriage, a cam adjustable on said carrier and co-operative with said follower, a pin located about equal distances from the ends of said cam and operatively 105 connected to move therewith, a plate fixed to said carrier and having a slot along which said pin is adapted to move, a link pivoted 110 at one end on said pin and adapted to move bodily therewith as well as to turn thereon, means for connecting the other end of said link to said fixed plate at any one of a number of different points and thus adjust the 115 cam and hold it in its adjusted position, and a second pin and slot connection between said fixed plate and cam, the slot of the last mentioned connection extending in the same direction and located in the same plane as 120 said first mentioned slot.

16. In a calculating machine, the combination of a carriage, a follower forming part of the totalizer-actuator control mechanism, a carrier adjustable to different positions along said carriage, a cam mounted to receive a rectilinear up and down adjustment on said carrier and guided against lateral movement on the carrier, a hand-actuated controlling member operatively con- 125 130

nected to move bodily up and down with the cam and also to move relatively thereto, a fixed part of the carrier having three notches therein at different elevations, and means carried by said controlling member and adapted to be seated in any of said notches to adjust the cam to and hold it in any of three positions determined by said notches.

17. In a calculating machine, the combination of a carriage, a follower forming part of a totalizer-actuator control mechanism, a carrier adjustable to different positions along said carriage, a cam adjustable on said carrier and co-operative with said follower, and means for controlling the adjustment of said cam comprising a slotted

plate having three end walls in the slot therein, a pin that enters said slot and the relative movement between which and said plate is limited and defined by said end walls 20 of the slot, means for effecting such relative movement, and means for causing such relative movement to be transmitted to the cam.

Signed at the borough of Manhattan, city 25 of New York, in the county of New York and State of New York, this 20th day of April, A. D. 1921.

ROBERT G. C. BOA.
